DREDGE

Walter W. Johnson, Berkeley, Calif., assignor to
 Walter W. Johnson Company, San Francisco,
 Calif., a corporation of Nevada

Application June 1, 1938, Serial No. 211,193

6 Claims. (Cl. 37—69)

My invention relates to ladder dredges, such as employed in gold dredging, and the broad object of the invention is to provide means for handling large boulders carried up the ladder so that the boulders may be removed simply and easily.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawings:

15 Figure 1 is a vertical sectional view taken through the hopper of a dredge embodying my invention, portions of the hopper wall being broken away to show the boulder dump mechanism; and

20 Figure 2 is a vertical sectional view of the same taken in a plane indicated by line 2—2 of Figure 1, showing the boulder discharge chute and the door in the side wall of the hopper through which the boulders are dumped.

25 Figure 3 is a vertical sectional view similar to Figure 2, and showing a modified form of construction; and

Figure 4 is a vertical sectional view of the same taken in a plane indicated by line 4—4 of Figure 3.

30 In ladder dredges, such as those employed in gold dredging, it frequently happens that a large boulder weighing perhaps a ton or more, is picked up by a bucket. The usual practice has been to stop the ladder and remove the boulder by block and tackle. This is an arduous and time taking operation. By the mechanism of the present invention these boulders are easily handled and dumped into a special discharge chute provided for that purpose, and this may be done without

40 stopping the ladder.

In terms of broad inclusion, the improved dredge comprises a ladder for elevating material and dropping it into a hopper, and a dump mechanism for deflecting a boulder from its normal path and discharging it into a special chute alongside the hopper.

In greater detail, and referring to Figures 1 and 2 of the drawings, a gold dredge embodying the invention comprises the usual ladder having buckets 2 linked together and running over an upper drive tumbler 3. The material carried up by the ladder buckets is dumped into a suitable hopper 4 having a chute 6 at the bottom for directing the material into a revolving screen 7. 55 This is all standard construction in gold dredges

of this type, and it is understood that the structural details may vary within wide limits.

If a large boulder is picked up by a bucket it is ordinarily removed before reaching the top of the ladder to prevent its being dumped into the hopper and fouling the mechanism. The buckets travel relatively slowly, and the customary practice has been that when the operator sees a boulder being elevated he stops the ladder. A crew of men was then required to rig up block and tackle to remove the boulder.

All this is avoided in the improved dredge of the present invention by a boulder dump mechanism mounted adjacent the upper end of the ladder. A boulder discharge opening 8 is 15 provided in the side wall of hopper 4 opposite the ladder and below the point where the buckets start discharging the elevated material into the hopper. A sliding door 9 is provided for normally closing this opening, and may be raised by an air cylinder 11 suspended from the superstructure of the dredge and having a duct 12 leading to the control cabin where the operator may open and close the door at will by manipulating a suitable valve.

25 Outside the opening 8 a chute 13 is arranged to receive the boulders and convey the same out over the edge of the dredge. The wall of the chute opposite the opening is suitably reinforced to withstand the shock of boulders being thrown 30 out, and the bottom of the chute is likewise reinforced as by rails 14.

35 Means are provided for deflecting a boulder from its path of fall and dumping it into chute 13. For this purpose a dump shelf or grid 16 is pivotally mounted adjacent the lower edge of opening 8 for movement from a boulder receiving position projecting horizontally into the hopper to a discharge position standing vertically outside the opening. The latter position is shown by dotted lines in Figure 1. In the receiving position the shelf extends across the path of falling material, and the open grid structure permits all but the large boulders to fall through. In normal operation of the dredge the shelf stands 40 outside the opening with the door closed behind it; the door being opened and the dump shelf lowered only when the operator sees a boulder being elevated.

45 A counterweight 17 is provided for balancing 50 the grid, and an air cylinder 18 is also connected to a lever on the shelf mounting shaft 19 for swinging the shelf from one position to another. Ducts 21 for admitting air into opposite ends of the cylinder lead to the control cabin where the 55

operator may swing the dump shelf in or out at will by manipulating suitable valves. After the operator feels the jar of a boulder landing on the shelf he swings the latter out to dump the boulder into chute 13. Door 9 is then closed and the dredge operates as usual until another boulder is picked up.

Since the ladder travels relatively slowly, and since the dump shelf 16 is positioned fairly well 10 below the point where the boulder drops out of its bucket, a watchful operator can swing the shelf up to discharge the boulder without stopping the ladder. If desired however the ladder may 15 be stopped momentarily until the boulder has been dumped.

The buckets clear the end of the shelf so that there is no danger of a bucket catching on it, but a large boulder on the shelf might project out 20 far enough to catch the down coming edge of a bucket if the boulder has not been thrown out fast enough, or if the ladder has not been stopped. To prevent jamming the mechanism in this event, 25 safety means are provided for allowing the shelf to be depressed. For this purpose the lower end of cylinder 18 is pivotally supported on an arm 22 having one end mounted on a pin 23 and the other end working in a guide slot 24. Arm 22 is supported by a bar 26 connected with a rocker arm 27 having heavy counterbalance 28 suspended 30 from the other end.

By this arrangement the actuating cylinder 18 may be depressed bodily to permit downward 35 yielding of the shelf, should the force bearing down on the latter be sufficient to overcome the holding force of weight 28. The latter is of course heavy enough and the mechanical advantages so designed that the cylinder will not go down under the ordinary efforts required to support and discharge a boulder.

Figures 3 and 4 illustrate a modified construction 40 in which a dump shelf or grid 29 is supported in operative position by a pair of side chains. Each chain 31 is suspended from a fixed element of the frame by a rod 32 held up by a heavy compression spring 33 to take up shock. The flexibility 45 of the chains permits them to fold so as to be out of the way for closing the door. The dump shelf is moved by an air cylinder 34 having its lower end supported directly on a girder of the dredge; there being no means allowing the unit to depress in this case because the arrangement 50 of the shelf at a higher point than in Figure 1 makes jamming highly improbable and a safety feature unnecessary.

A variant arrangement of door cylinder 35 is 55 also shown to eliminate the suspended cylinder shown in Figure 2. The boulder discharge chute is also somewhat different in that an arrangement of blocks 37 is provided under the head end to take up the shock of outcoming boulders.

Another feature shown in Figure 3 is a gate 38 for holding the boulders from immediately

rolling completely down the chute. Such a gate is desirable to hold back the boulders so that they can all be dumped at one point instead of strewn about the bottom of the area being dredged. The gate 38 is preferably in the form 5 of a grid pivoted at its upper end and held down in the chute by a pair of elbow arms 39. The elbow pin is slightly below center when the arms are extended to keep them from knifing up and a strap 41 across the top holds them from buckling 10 down. A rope 42 connecting the elbow pin with a lever 43 permits an operator to break the arms and allow the gate to swing up to free the collected boulders. A counterweight 44 keeps the gate up, and a lever 46 provides means for an operator 15 to lower the gate.

I claim:

1. A dredge comprising a ladder for elevating material, a pivotally mounted dump shelf extending across the path of material dropped from the ladder for catching a boulder, means for swinging the shelf upwardly to discharge the boulder, and means for yieldably supporting the shelf in its extended position.

2. A dredge comprising a ladder for elevating material, a pivotally mounted dump shelf extending across the path of material dropped from the ladder for catching a boulder, means for swinging the shelf upwardly to discharge the boulder, and counterbalance means for yieldably supporting the shelf in its extended position.

3. A dredge comprising a ladder for elevating material, a pivotally mounted dump shelf extending across the path of material dropped from the ladder for catching a boulder, a pressure fluid cylinder operably connected to swing the shelf upwardly for discharging the boulder, and means for yieldably supporting the cylinder.

4. A dredge comprising a ladder for elevating material, a pivotally mounted dump shelf extending across the path of material dropped from the ladder for catching a boulder, a fixed element above the shelf, flexible means for suspending the free end of the shelf from said fixed element, and means for swinging the shelf upwardly to discharge the boulder.

5. A dredge comprising a ladder for elevating material, a dump shelf extending across the path of material dropped from the ladder for catching a boulder, means for moving the shelf to discharge the boulder, and means for yieldably supporting the shelf in its extended position.

6. A dredge comprising a ladder for elevating material, a hopper into which the material from the ladder is dropped and having an opening in the side thereof, a dump shelf extending into the hopper for catching a boulder, means for yieldably supporting the shelf in extended position, means for moving the shelf to discharge the boulder through said opening, and a door for closing the opening.

WALTER W. JOHNSON.
